UNITED STATES PATENT OFFICE.

DANIEL M. COOPER, DECEASED, LATE OF ROCHESTER, NEW YORK, BY GEORGE B. CAUDLE, EXECUTOR, OF ROCHESTER, NEW YORK, ASSIGNOR TO THE AMERICAN LAUNDRY MACHINERY COMPANY, OF NORWOOD, OHIO, A CORPORATION OF OHIO.

GARMENT-PRESSING MACHINE.

1,332,711.

Specification of Letters Patent.

Patented Mar. 2, 1920.

Original application filed March 20, 1912, Serial No. 685,115. Divided and this application filed October 6, 1917. Serial No. 195,186.

To all whom it may concern:

Be it known that DANIEL M. COOPER, deceased, late a citizen of the United States, and formerly a resident of Rochester, county 5 of Monroe, State of New York, is the inventor of certain new and useful Improvements in Garment-Pressing Machines, of which the following is a specification.

This invention relates to garment pressing machines, and more particularly to that 10 class of machines including a stationary lower pressing member or garment support and an upper pressing member or head movable vertically with relation to the lower 15 pressing member and adapted to be brought into pressing relation therewith to press a garment or fabric lying between said members.

The object of the invention is to improve the 20 mechanism or devices for producing pressure upon the garment, and particularly to provide improved means for adjusting the relation between the operating mechanism and the swinging arm or lever carrying the upper 25 pressing member, so as to enable the operator to readily adjust the degree or amount of pressure imparted to the work. More particularly, the object of the invention is to provide an adjusting member carried by the 30 swinging arm which supports the head and is rotatable relative to said arm, said adjusting member being connected to the toggle or other arm operating mechanism above said arm, or lying in a position above said 35 arm, where it is always conveniently accessible and capable of being easily operated.

A further object of the invention is to provide improved mechanism connecting the operating treadle and the swinging pressing 40 head supporting lever so as to obtain the most efficient application of power and maximum pressure with minimum effort, and also secure wide separation or working clearance between the two pressing members 45 with minimum swing or movement of the operating treadle, both to enable the operator to manipulate the garment on the garment support when the press is open and to also avoid such wide range of operating 50 movement of the treadle as would inconvenience the operator and interfere with most efficient foot pressure.

Further objects of the invention are in part obvious and in part will appear more in detail hereinafter.

55

The invention comprises the construction and arrangement of parts hereinafter described and claimed.

This application is a division of a prior 60 application of the above named Daniel M. Cooper, deceased, for garment pressing machines, upon which Patent No. 1,245,571 issued Nov. 6, 1917, to which reference may be had for a more complete description of the mechanism.

65 Referring to the drawings, Figure 1 is a side elevation of one form of garment pressing machine embodying the invention, the pressing members being in open or release position; Fig. 2 is a detail cross section, 70 on a larger scale, the adjusting arm or handle being shown in a different position; and Fig. 3 is a plan view of the machine shown in Fig. 1.

The machine shown in the drawings 75 comprises a suitable frame 1 carrying the stationary lower pressing member or bed 2, which has a padded surface 3 on which the garment to be pressed is supported and which may be suitably shaped to conform 80 to the requirements of the operator or may be adapted particularly for pressing any desired kind of work. At the rear of the frame is an upwardly extending standard or support 4 to which is pivotally connected a swinging frame or two armed lever

85

5 on which is mounted the upper pressing member or head 6, shaped to correspond to the bed 2 and provided on one of its arms with a pressing pad 7. Said upper pressing member may be heated in any suitable manner such as by steam circulated from the supply pipe 8 through the hollow chamber of said head to the outlet pipe 9. The weight of said head and lever may be more 90 or less counter-balanced by a weight 10 adjustably supported on the rear arm of the lever behind the pivot 10 on which the lever turns. The pressing head may be brought down into coöoperating pressing relation 100 with the bed by pulling down upon the same with the hand, for which purpose it is usually provided with a conveniently located handle 12.

95

100

Suitable mechanism is also provided for enabling the head to be applied with powerful pressure to the bed for securing the pressure upon the work necessary for effective 5 ironing or pressing. This mechanism, as shown, is actuated by a foot treadle 13 pivoted at 14 in the frame and connected by a link 15 to one arm of a lever 16 pivoted at 17 in the frame. The other arm of said 10 lever is connected by a link 18 to suitable toggle mechanism for actuating the swinging lever 5. This toggle mechanism comprises two members pivotally connected to each other at the flexible joint 19, which is 15 also the point of connection of said toggle mechanism to the operating link 18, as shown in Fig. 1. The lower member of the toggle mechanism is a link 20 pivotally connected at 21 to a suitable support, such as 20 the stationary frame. The upper member of the toggle mechanism includes relatively adjustable members adapted when adjusted to vary the pressure between the head and garment support when the press is closed. 25 This upper toggle member includes a member 22 having a threaded socket 23 to receive the threaded lower end of a rod 24 extending upwardly to the rear portion of the swinging lever 5 where it passes through a 30 transverse substantially vertical opening in a sleeve member 25 mounted to turn on a shaft or rod 26 carried by the two side members 27 of the lever 5. The shoulder 28, where a reduced portion 29 of the rod 24 35 enters the sleeve 25, transmits the upward thrust of the toggle mechanism to the arm. Rod 24, above the sleeve 25, is provided with suitable operating means adapted when operated to vary the working pressure, as 40 aforesaid. This means, as illustrated, comprises a head 30 to which is pivotally connected a swinging handle 31 having a toothed portion 32 adapted to enter any one of a series of circumferentially spaced 45 notches or recesses 33 in a cup shaped upward extension of the sleeve 25.

The lever 5 is normally held in its upper open or release position by a tension spring 34 connected at one end to the rear portion 50 of the lever 5 and at its opposite end to a support, such as a hook 35 on a portion of the stationary frame 1.

Fig. 1 shows the press in its open or release position. The head 6 is up, the rear 55 arm of the lever 5 is down, the toggle mechanism is broken, and the pressure treadle 13 is up. If the pressure of the foot of the operator is applied to the treadle 13 the lever 16 is turned in a clockwise direction 60 and the upward thrust of the link 18 is transmitted to the toggle mechanism, causing the head to move downward into pressing relation with the bed. The press is so arranged that when the treadle 13 reaches 65 its lower position and its motion is stopped

either by contact with the floor or a suitable stop device the pivot 19 of the toggle mechanism is moved a little beyond a straight line joining the pivots 21 and 26. The press is therefore locked in closed position, as is 70 usual with toggle operated devices. The pressure between the head and bed in this position may be adjusted by lifting the handle 31 to release its tooth 32 from the notches 33 and by means of said handle 75 turning the rod 34 to screw the same into or out of the socket 23 and then reengaging handle 31 with a notch 33. This adjustment is usually made when the machine is in release position, and in effect raises or lowers, 80 as the case may be, the level of the point of connection of said toggle mechanism to the swinging lever. The adjusting device, to-wit, the handle 31, is rotatably connected by the rod 24 to the lever 5, but its point of 85 connection to the rod 24 has no vertical motion relative to the lever. In fact the rod 24 is swiveled to the lever. Consequently its position is fixed relative to the lever and the adjusting device is always in convenient 90 position for operation. The adjusting device is also so located that when the press is released it does not move down into the machine or back of other parts of the mechanism where it is more or less inaccessible 95 and cannot be readily operated, as is sometimes the case in this class of machine, but said device is always exposed or readily accessible, its very position being an incentive to the operator to make such adjustments as 100 may be necessary from time to time.

The convenient position and arrangement of the adjusting device always serves as an incentive to the operator to make adjustment of the press and thereby produce the 105 best pressing effect.

The operating mechanism connecting the foot treadle and swinging lever is highly efficient and practical. The rear arm of lever 16 and link 18 together form auxiliary 110 toggle means which exerts its effort upon the pivot 19 joining the main toggle members. Both sets of toggles straighten and break together and the powerful effect and increased leverage secured during the latter 115 portion of the straightening movement of the auxiliary toggle members 16, 18 is exerted upon the main toggle members during the final straightening movement thereof and at a time when maximum power is required. By properly proportioning the lever arms and toggle members with relation to each other the mechanism can be so arranged, and is so shown, that the foot treadle has a limited range of movement, 120 in practice about ten inches, which is the most convenient range for foot operation. Greater range of movement would interfere with efficient application of pressure by the foot. This same range of movement of the 125 130

foot treadle secures wide opening between the pressing head and garment support when the press is open, thereby enabling the operator to readily manipulate the garment 5 on the support notwithstanding the relatively wide pressing area and the absence of relative lateral movement between the pressing members. At the same time the relatively long length of the foot treadle 10 avoids the "choppy" effect of a short treadle and maintains the foot receiving portion of the treadle in more nearly uniformly horizontal position throughout its range of movement.

15 What is claimed is:—

1. A garment press, comprising a garment support, a swinging lever carrying a press head, means for actuating said lever, said means comprising toggle mechanism 20 and a connection to said lever and including relatively adjustable members adapted when adjusted to vary the pressure between the head and garment support when the press is closed, and means connected to one of said 25 members above said lever for relatively adjusting said members.

2. A garment press, comprising a frame, garment support carried thereby, said frame having a supporting portion spaced 30 rearwardly from said garment support, a two armed lever pivoted to the supporting portion of said frame, the front arm of said lever carrying a press head for co-operation with said garment support, said lever lying 35 substantially horizontal when the head is in pressing engagement with the garment support, toggle links one connected to the rear arm of said lever and another to a support beneath the same, and means for 40 straightening and breaking said toggle links, comprising a foot treadle, a two armed operating lever pivoted in the frame, a link connecting said treadle with the forward arm of said operating lever, and a link oper- 45 atively connecting the rear arm of said operating lever to said toggle links, the rear arm of said operating lever and the link connected thereto forming a second toggle which straightens and breaks with the first 50 toggle and extends substantially trans- versely thereto when the press is closed.

3. A garment press, comprising a frame, a garment support carried thereby, said frame having a supporting portion spaced 55 rearwardly from said garment support, a two armed lever pivoted to the supporting portion of said frame, the front arm of said lever carrying a press head for co-operation with said garment support, said 60 lever lying substantially horizontal when the head is in pressing engagement with the garment support, toggle links one connected to the rear arm of said lever and another to a support beneath the same, and means 65 for straightening and breaking said toggle

links, comprising a pair of toggle links one operatively connected to said first-named toggle links and the other to a support, a foot treadle, and a link operatively connecting said foot treadle to said second pair 70 of toggle links for operating the same, said two pairs of toggle links straightening and breaking together and extending substantially transversely to each other when the press is closed. 75

4. A garment press, comprising a frame, a garment support thereon, a substantially straight lever of the first kind pivotally mounted in the frame, a press head carried by one arm of said lever and adapted to co-operate with said garment support, a pivoted foot treadle, main toggle links one of which is connected to the rear arm of said lever and the other to a relatively fixed part, and auxiliary toggle members effective upon 85 said main toggle links and connected to a relatively fixed part and to said treadle, both sets of toggles moving toward straightened position as the treadle is depressed.

5. A garment press, comprising a frame, 90 co-operating relatively movable pressing members carried thereby, a pair of pivotally connected toggle members operatively connected to said pressing members, said members being so arranged that straightening 95 movement thereof causes relative approach of the pressing members, and toggle means adapted when moved toward straightened position to produce straightening movement of said toggle members. 100

6. A garment press, comprising relatively movable pressing members, a pair of toggle members operatively connected thereto and adapted when straightened to produce pressure between said pressing members, and 105 a second pair of toggle members operatively connected to said first named pair for straightening the same, said two pairs of toggle members extending substantially transversely to each other when the press 110 is closed.

7. A garment press, comprising relatively movable pressing members, a pair of toggle members operatively connected thereto and adapted when straightened to produce pressure between said pressing members, and a second pair of toggle members operatively connected to the flexing joint of said first named pair for straightening the same, said two pairs of toggle members being so ar- 115 ranged that when the press is closed a line joining the outer ends of the toggle members of one pair intersects a line joining the outer ends of the toggle members of the other pair, whereby the increasing power 120 effect of one pair is applied to the other pair as the power effect of the latter pair increases. 125

8. A garment press, comprising a frame having a supporting portion, a garment sup- 130

- port mounted on the frame in front of said supporting portion, a coöperating press head, head swinging mechanism including an arm pivoted in said supporting portion 5 and having a member depending therefrom and swinging forwardly or rearwardly with movement of said head, a two-armed operating lever pivoted intermediate its ends in the frame, a connection between said depending member and one arm of said two-armed lever and forming a toggle with said arm, a treadle, and a connection between said treadle and the other arm of said two-armed lever.
- 10 9. A garment press, comprising a frame having a supporting portion, a garment support mounted on the frame in front of said supporting portion, a coöperating press head, head swinging mechanism including an arm pivoted in said supporting portion and having a member depending therefrom and swinging forwardly or rearwardly with movement of said head, a toggle lever operating member pivoted in the frame, a treadle, connections between said treadle and operating member, and a toggle link connecting said depending member and said operating member and connected to said operating member at a greater distance from its pivot than the distance from said pivot of the treadle connection to said operating member.
- 15 10. A garment press, comprising a frame, a garment support thereon, a press head, and operating means therefor, comprising a lever pivoted in said frame and carrying said head, a member depending from said lever and movable forwardly or rearwardly with movement of said head, a two-armed operating lever pivoted in the frame, a link pivotally connected at its opposite ends to said depending member and to one arm of said operating lever and with said arm forming a toggle, a relatively long foot treadle pivoted in the rear portion of the frame behind the pivot of said operating lever, and a link connecting the forward portion of
- 20 25 30 35 40 45
- said foot treadle to the other arm of said two-armed operating lever.
11. A garment press, comprising a frame, 50 a garment support thereon, a press head, and operating means therefor, comprising a lever pivoted in said frame and carrying said head, a member depending from said lever and movable forwardly or rearwardly 55 with movement of said head, a treadle lever pivoted near the rear of said frame and extending outwardly from the front thereof, a toggle lever member pivoted in the frame above said treadle, connecting means between the front portion of said treadle lever and said toggle lever member, and a link connecting said depending member to said toggle lever member and forming a toggle therewith, the connection of said link to said 60 toggle lever member being farther from the pivot of said toggle lever member than the treadle connection thereto.
12. A garment press, comprising a frame, 70 a garment support thereon, a press head, and operating means therefor, comprising a lever pivoted in said frame and carrying said head, a member depending from said lever and movable forwardly or rearwardly 75 with movement of said head, a two-armed operating lever pivoted in the frame and having a short arm and a longer rear arm, said short arm extending upwardly and said rear arm downwardly when the press is open, a relatively long foot treadle pivoted 80 in the rear of the frame below said operating lever and extending outwardly from the front of the press, a link connecting the forward portion of said treadle to said short lever arm, and a link connecting said depending member and said longer lever arm 85 and cooperating as a toggle therewith.
- In testimony whereof, I, GEORGE B. CAUDLE, executor of the estate of DANIEL M. COOPER, deceased, hereby affix my signature. 90
- GEORGE B. CAUDLE,
Executor of the Estate of Daniel M. Cooper, deceased.
